UNITED STATES PATENT OFFICE.

SILAS A. STRICKLAND, OF DETROIT, MICHIGAN, ASSIGNOR TO DETROIT ACCESSORIES CORPORATION, OF DETROIT, MICHIGAN, A CORPORATION OF MICHIGAN.

PUMP FOR MOTOR-VEHICLES.

1,376,903.

Specification of Letters Patent.

Patented May 3, 1921.

Original application filed December 13, 1915, Serial No. 66,513. Divided and this application filed August 5, 1918. Serial No. 243,498.

To all whom it may concern:

Be it known that I, SILAS A. STRICKLAND, a citizen of the United States of America, residing at Detroit, in the county of Wayne 5 and State of Michigan, have invented certain new and useful Improvements in Pumps for Motor-Vehicles, of which the following is a specification, reference being had thereto in the accompanying drawings.

10 This invention relates to matters divided out from my former application filed December 13, 1915, Serial No. 66,513 for pumps for motor vehicles, which application has matured into Patent No. 1,294,564, dated 15 Feb. 18, 1919, wherein the subject matter thereof is directed to the supporting of a pump upon the end of an engine shaft by means passing loosely through an opening in a chassis element, which matter is common to both applications and is shown in 20 Figs. 1 to 6 inclusive of the drawings hereof, the subject matter of this application referring more particularly to a manner of detachably supporting a pump upon the front 25 end of a motor vehicle and driving the same from the shaft of the motor, the invention consisting in the novel construction and arrangement of parts as hereinafter more fully set forth, reference being had to the 30 accompanying drawing, but it is to be understood that the structural elements are susceptible to such variations in their construction, arrangement and combination as fall 35 within the scope of the appended claims.

35 In the drawings,

Figure 1 is an elevation of an air pump, a portion of an engine shaft, and a portion of a chassis, the latter being in section and a portion of the pump broken away and in 40 section;

Fig. 2 is a plan view of the same;

Fig. 3 is a front elevation of the same;

Fig. 4 is a cross sectional view taken on the line IV-IV of Fig. 3;

45 Fig. 5 is a perspective view of a portion of a pump ear;

Fig. 6 is a perspective view of the detached keeper;

50 Fig. 7 is an elevation of an air pump, a portion of an engine shaft, and a universal coupling shaft, the latter partly broken away and partly in section;

Fig. 8 is a plan of the same;

Fig. 9 is a front elevation of the same; and

55

Fig. 10 is a cross sectional view taken on the line X-X of Fig. 9.

The drawings show portions of a motor vehicle, as an engine or motor shaft 1 having a transverse pin 2 adjacent the outer end 60 thereof; a portion of a radiator 3, and a chassis element, as a transverse channel member 4 having an opening 5 in axial alinement and in proximity to the outer end 65 of the engine shaft 1.

Referring now to Figs. 1 to 6 inclusive, an air pump 6 is associated with the above elements, said air pump having a back plate 7 provided with a bushing 8 adapted to extend into the opening 5 of the channel member 4. 70 The bushing 8 constitutes one of the bearings of a pump shaft and the rear end of said pump shaft terminates in a rigid and integral coupling socket 10, having the rear end thereof slotted, as at 12, whereby the 75 coupling socket can be slipped on the end of the shaft 1 and placed in engagement with the pin 2 thereof for rotative continuity with the engine shaft. The outer end 80 of the engine shaft and the coupling socket 10 are of sufficient length whereby after the air pump is placed in engagement with the engine shaft said shaft constitutes the sole means of supporting said air pump and this constitutes an important feature of my 85 invention.

It is now apparent that if the engine shaft 1 be driven, the air pump would be bodily rotated and to prevent such movement of the air pump and permit the shaft 9 to perform its usual function in connection with the pump, I have devised means in connection with the plate 7 and the channel member 4 for holding the pump practically stationary. Such means however does not constitute a support for the pump, as said pump is solely supported by the engine shaft, but simply maintains the pump in an operative useful position.

The channel member 4, contiguous to the 100 opening 5, has openings 13 to receive keepers in the form of bushings 14. The inner ends of the bushings are exteriorly screw-threaded to receive nuts 15 and the outer ends of said bushings terminate in cylindrical heads 16 having radially disposed 105

grooves 17 in communication with the bores of said bushings.

Slidable in the keepers of the channel member 4 are retaining members comprising pins 18 having the inner ends thereof provided with abutments 19 for coiled compression springs 20 encircling the inner ends of the pins 18, said springs holding the retaining members in a retracted position.

10 The outer ends of the pins 18 terminate in cranks 21 having finger pieces 22 and said cranks are normally held in engagement with the heads 16 of the keepers and in the grooves 17 of said heads, thereby preventing rotation of the retaining member until the cranks 21 are removed from the grooves 17. The cranks 21 of the retaining members are adapted to engage bifurcated or slotted ears 23 forming the ends of the 20 plate 7, and said ears have grooves 24 in communication with the slots thereof to receive the cranks 21 of the retaining members. By reference to Fig. 3 it will be noted that the slots or bifurcations of the ears 23 are of sufficient size to receive the retaining members and with said members in a lateral position, the air pump can be easily placed in an operative position relative to the engine shaft and then the retaining members 30 swung to vertical positions simply to prevent the air pump from rotating. With the retaining members in unlocked positions there is sufficient clearance between said members and ears 23 to permit of the air pump being properly positioned on the engine shaft, and such clearance emphasizes the fact that the air pump is solely supported by its operating means.

As heretofore stated, there are times when 40 the relative position of the engine shaft and the channel member or a similar support is such as to prohibit the operation of an air pump by the engine shaft without the intervention of a transmission device, 45 and with this inequality in mind, reference will be had to Figs. 7 to 10 inclusive. In these views the reference numeral 40 denotes an engine shaft provided with a transverse pin 41; 42 a channel member having an 50 opening 43; 44 an air pump, and 45 a plate secured to the air pump and provided with a bushing 46 for the pump shaft 47. The pump shaft 47 is slotted, as at 51, and provided with a socket 48 to receive the reduced 55 ball or spherical end 49 of a universal coupling shaft 50. The ball or spherical end of the shaft has a transverse pin 52 extending into the slots of the pump shaft to establish rotative continuity between the pump shaft 60 and the universal coupling shaft, and a coiled compression spring 53 encircles the reduced end of the universal coupling shaft to assist in preventing accidental displacement of the same. The opposite end of the 65 universal coupling shaft terminates in a

socket 54 provided with slots 55, said sockets receiving the end of the engine shaft 40 with the transverse pin 41 extending into the slots 55 to establish rotative continuity between the universal coupling shaft and the 70 engine shaft. The pin and slot connection between the pump shaft and the universal coupling shaft prevents accidental displacement of the latter relative to the former, and facilitates placing the universal coupling shaft in position as a transmission device from the engine shaft to the pump shaft, yet allowing longitudinal and angular adjustment of the universal coupling shaft relative to the pump shaft. 75

When the universal coupling shaft 50 is used it is necessary that the air pump be supported not only against rotation, but by some means other than the shaft 50 or the engine shaft 40, therefore the channel member 42 is provided with studs 56 to receive apertured ears 57 of the plate 45. The studs 56 have conical heads 58 to facilitate placing the ears 57 on said studs and said ears have pivoted slotted resilient latch 90 members 59 that can be easily shifted into engagement with the studs 56, behind the heads 58 thereof to lock the ears 57 in engagement with the channel member 42, whereby the air pump will be firmly supported relative to said channel member. This manner of connecting the air pump to the member 42 permits of said air pump being quickly and easily installed, and while the engine shaft 41 has been illustrated in 100 alinement with the opening 43 of the member 42, it is apparent that the opening 43 may just as readily be out of alinement with the engine shaft, as the universal coupling shaft constitutes means whereby power may 105 be transmitted to the air pump by the engine shaft.

What I claim is:—

1. In combination with a fixed portion and a driven shaft of a motor vehicle and a detachable tire pump having a pump shaft in substantial alinement with and detachably coupled to the driven shaft, means for engaging the fixed portion of the vehicle to prevent rotation of the pump body in both 110 directions in respect to the driven shaft, said means comprising a member that is brought into rotation preventing relation with the fixed portion by a sliding endwise movement 115 longitudinally of the shaft.

2. In combination with the engine shaft and with a fixed portion of a motor vehicle, said fixed portion including the front cross bar, a detachable tire pump having a pump shaft in substantial alinement with and detachably coupled to the engine shaft, and means adapted to be brought into position for preventing rotation of the pump body 125 in respect to the engine shaft by an endwise movement other than rotative longitudinally 130

- of the shaft, said means including a member forming a connection between said pump and cross bar to prevent rotation of the pump body in both directions.
- 5 3. In combination with the engine shaft and a fixed cross member of a motor vehicle, a pump having a shaft, means for detachably coupling the pump and engine shafts, and members on the pump body and cross
- 10 member adapted to be inter-engaged by a movement other than rotative of the pump body toward the cross member to prevent rotation of the pump body in either direction about its shaft.
- 15 4. The combination with a fixed portion and a driven shaft of a motor vehicle, a pump detachably supported by said fixed portion and having a shaft detachably connected to said driven shaft, inter-engaging
- 20 means for preventing rotation of the pump about its shaft in either direction and for preventing movement of said pump in a direction longitudinally of its shaft relative to said fixed portion, said means being
- 25 brought into inter-engaging relation by a sliding movement longitudinally of the shaft.
5. The combination with a chassis cross-member and a driven shaft of a motor vehicle, a tire pump detachably supported by said cross member and having a shaft detachably connected to the driven shaft, a holding member adapted to be brought into position to prevent rotation of the pump
- 30 about its shaft by a movement longitudinally of the shaft other than rotative, and locking means for the holding member to prevent movement of the pump relative to the cross member in a direction longitudinally of the
- 35 pump and driven shafts.
- 40 6. The combination with a chassis cross-member and a driven shaft of a motor ve-
- hicle, a tire pump having a shaft detachably connected to the driven shaft, and a holding member projecting from the cross member in a direction longitudinally of said shafts to engage the pump upon movement other than rotative of the pump body toward the cross member and prevent rotation of the pump about its shaft in either direction.
- 45 7. The combination with a chassis cross member and a driven shaft of a motor vehicle, a tire pump having a shaft detachably connected to the driven shaft, a holding member projecting from the cross member to engage the pump upon sliding movement longitudinally of the shaft of the pump toward said cross member and prevent rotation thereof about its shaft, and locking means to engage said holding member and prevent movement of the pump in a direction longitudinally of its shaft relative to said cross member.
- 50 8. The combination with a chassis cross member and a driven shaft of a motor vehicle, a tire pump detachably supported by the cross member and having a shaft extending in a direction longitudinally of the driven shaft, and universal coupling means connecting said shafts and comprising two members, one formed with a socket at its end and slots in its sides opening into said socket, and the other member formed with a head projecting into the socket with projections engaging said slots, and a spring
- 55 to normally hold one member projected from the other with said projections engaging one end of said slots.
- 60 In testimony whereof I affix my signature in the presence of two witnesses.
